UNITED STATES PATENT OFFICE.

CLYDE GEORGE POST, OF NORTH ENGLISH, IOWA.

STRINGED MUSICAL INSTRUMENT.

1,410,504.

Specification of Letters Patent. Patented Mar. 21, 1922.

Application filed October 14, 1920. Serial No. 416,836.

To all whom it may concern:

Be it known that I, CLYDE GEORGE Post, a citizen of the United States, residing at North English, in the county of Iowa and 5 State of Iowa, have invented certain new and useful Improvements in Stringed Musical Instruments, of which the following is a specification.

The invention relates to improvements in 10 musical instruments and has particular reference to stringed instruments, such as the guitar, mandolin, or the like in which the strings are plucked with the fingers or vibrated by means of a "pick".

15 In many instruments, of which the guitar is an example, the strings lie in a horizontal plane substantially parallel with the horizontal plane of the sound box and when the strings are plucked, by the fingers or by use 20 of a pick, they are thus caused to vibrate in planes that are also substantially horizontal so that the plane of vibration does not pass through the sound box but is in every case across the top of the box.

25 By plane of vibration I mean the direction of the initial motion imparted to the string when it is stressed and released to cause its vibration.

In guitars, or the like, strings are stressed 30 or deflected laterally and not in a direction toward and from the sound box as in my improved instrument.

One of the objects of the invention is to 35 provide a musical instrument in which a plurality of strings are arranged in a plane perpendicular to the upper face of sound box, with which they are associated, so that they may conveniently be stressed or deflected by the performer in direction toward 40 and from the sound box, thereby causing the plane of vibration to pass through the box instead of passing across the top thereof.

Another object is to arrange the finger-board, upon which the strings are supported, sufficiently high above the sound box to permit the hand of the performer to be freely moved over the frets and about the finger-board, in the space between the latter and the sound box, and the arrangement is such as to permit the sound box to be extended in length substantially equal to the length of the finger-board, thus increasing the volume of sound and rendering substantially the entire finger-board available

for manipulation by the fingers of the performer.

Another object is to provide a bridge for the strings, that will transmit the vibrations from the strings to the box in line with the 60 vibrations.

Other, further and more specific objects of the invention will become readily apparent, to persons skilled in the art, from a consideration of the following description, 65 when taken in conjunction with the drawings, wherein:

Figure 1 is a plan view of the improved instrument.

Fig. 2 is a side elevation thereof, and

Fig. 3 is an end elevation.

In all the views the same reference characters are employed to indicate similar parts.

In the exemplification shown in the drawings 5 is the sound box, 6 is the finger-board and 7 is the arch for supporting one end of the finger-board, having two supports, 8 and 9, connected to the inert outer edges of the sound box 5.

The string bridge 10 passes across the finger-board 6 and positions the strings 11 slightly away from the board. The lower end of the bridge 10 is bifurcated having a leg 12 and another leg 13 to straddle the 85 opening 14 in the top 15 of the sound box.

16 is the bottom wall of the sound box, there being a vertical wall 17 between it and the top wall 15. The sound box, in the present instance is shown as pear shaped, 90 having a projection 19 extending laterally therefrom, which engages the tuning peg end 20 of the finger-board, and is one of the means in conjunction with the arch 7, by which the finger-board is supported upon the sound box, thus providing three inert points of support for the finger-board. The strings are fixed to a tail piece 21, at the other end of the finger-board. The 95 frets 22, that extend transversely of the finger-board, may be continued substantially the full length of the board, and thus the entire length of the finger-board may become available.

Of course, it is obvious that this invention 105 may extend to and be incorporated in other instruments of the same general character, such as the mandolin, banjo, and the like.

While I have here shown a single embodiment of the invention for purpose of 110

clear disclosure, it is clearly apparent that changes may be made in the arrangement and configuration of the parts within the scope of the appended claims.

5 Having described my invention what I claim is new and desire to secure by Letters Patent is:—

1. A musical instrument having an oblong sound box and a plurality of strings arranged in a plane perpendicular to the face of the box and each string parallel with the longest axis of the box.

2. A musical instrument having an oblong sound box and a plurality of strings arranged in a plane perpendicular to the face of the box and with effective lengths within the lineal limit of the box and parallel with the longest axis of the box.

3. A musical instrument having an oblong sound box; a finger-board extending substantially the length thereof and elevated thereabove and a plurality of strings in substantially a single plane perpendicular to the face of the box, supported on said finger-board and parallel with the longest axis of the box.

4. A musical instrument having a sound box; a finger-board extending substantially the length thereof and elevated thereabove to permit access to the strings between the

board and box; a plurality of strings in a plane perpendicular to the face of the box and a three-point support for the board, on the box.

5. A musical instrument having a sound box substantially pear shape in outline; a finger-board extending from the widest portion to the smaller end of the box; an arch extending across the widest end of the box to support one end of the finger-board and a single support for the other end of the finger-board extending from the smaller end of the box, said supports spacing said finger-board from the box to render substantially the entire length of the finger-board available for fingering.

6. A musical instrument having a sound box; a plurality of strings in a single plane perpendicular to the face of the box, the effective length of which is immediately above the box; a finger-board, upon which the strings are supported, spaced away from the box to render the strings available for fingering through said space and a string bridge extending across and under said strings and in contact with said box.

In testimony whereof I hereunto subscribe my name.

CLYDE GEORGE POST.
